UNITED STATES PATENT OFFICE

EVERETT J. McGARRY, OF CHICAGO, ILLINOIS

DESIGN FOR A COMBINATION DISPLAY BOARD AND TRAY

Application filed February 27, 1933. Serial No. 47,326. Term of patent 7 years.

To all whom it may concern:

Be it known that I, EVERETT J. McGARRY, a citizen of the United States, residing at Chicago, in the county of Cook and State of Illinois, have invented a new, original, and ornamental Design for a Combination Display Board and Tray, of which the following is a specification, reference being had to the accompanying drawing, forming part thereof.

In the drawing:

The figure shows a perspective view of a combination display board and tray embodying my new and original design.

I claim:

The ornamental design for a combination display board and tray as shown.

EVERETT J. McGARRY.
